United States Patent Office

Des. 194,244
Patented Dec. 18, 1962

194,244

JUG

Donald P. Denhoff and Dale R. Brown, Saline, Mich.,
assignors to Hoover Ball and Bearing Company, Ann Arbor, Mich., a corporation of Michigan

Filed July 27, 1961, Ser. No. 66,096

Term of patent 14 years

(Cl. D58—5)

The dominant features of our design reside in the portions shown in full lines.

We claim:

The ornamental design for a jug, as shown and described.
